UNITED STATES PATENT OFFICE.

GEORGE IRVING GILCHREST, OF WILKINSBURG, PENNSYLVANIA, ASSIGNOR TO WESTINGHOUSE ELECTRIC & MANUFACTURING COMPANY, A CORPORATION OF PENNSYLVANIA.

INSULATOR.

Application filed October 8, 1918. Serial No. 257,334.

To all whom it may concern:

Be it known that I, GEORGE IRVING GILCHREST, a citizen of the United States, and a resident of Wilkinsburg, in the county of Allegheny and State of Pennsylvania, have invented a new and useful Improvement in Insulators, of which the following is a specification.

My invention relates to insulators of the pin type and particularly to the pins therefor.

One object of my invention is to provide a device of the above-indicated character that shall be rugged and durable in construction, inexpensive to manufacture and effective in operation.

Another object of my invention is to provide an insulator pin of wood or other suitable material that shall be protected from damage, such as charring, from corona and static or flash-over discharges thereon.

Another object of my invention is to provide an insulator pin of readily-machinable material, such as wood, that may be turned or machined to any of many different shapes without the expense, time or labor required to perform the same operations on a metal pin and have substantially the advantages of both a metal and a non-metallic pin.

A further object of my invention is to provide an insulator pin of wood or other material, subject to deterioration by exposure to the weather or other influences, with a metal protective coating that shall prolong the life and maintain the effectiveness of the pin.

In practicing my invention, I provide an insulator pin of wood or other non-metallic material having a metallic coating that may be electrolytically deposited, sprayed, painted or otherwise placed thereon.

The single figure of the accompanying drawings is a view, partially in side elevation and partially in section, of an insulator having a supporting pin embodying my invention.

An insulator 1 may comprise superposed members 2 having petticoats 3 and support a conductor 4 by means of a tie wire 5 or other suitable device. A pin 6, having screw-threaded portions 7 and 8 at its upper and lower ends, respectively, may sup-

port the insulator 1 on a usual cross arm 9 or other device and be provided with a metal coating 10. The coating 10 may entirely 55 cover the pin 6 and be electrolytically deposited, sprayed, painted, or otherwise placed thereon. When so treated, the pin has the appearance and many of the characteristics of an all-metal pin, such as longevity, protection against fire and the deteriorating effects of air, water, or other influences and may be effectively formed of many varied or special shapes more readily than metal. 60

Further, an insulator pin of this character may be considerably lighter in weight than an all-metal pin and be less likely to crack the porcelain insulator by reason of the unequal expansion and contraction of 65 metal and porcelain.

While I have shown and described a particular form of my invention, many changes may be effected therein without departing from the spirit and scope thereof, as set 70 forth in the appended claims.

I claim as my invention:

1. A support for an insulator comprising a pin having a wooden core and an outer metallic protective sheathing, whereby said 80 core is rendered impervious to moisture and fire resistant.

2. A support for an insulator comprising a pin having a fibrous core and an outer metallic protective sheathing, whereby said 85 core is rendered fire resistant.

3. A support for an insulator comprising a pin having a core subject to deterioration by moisture and an outer metallic protective sheathing whereby said core is rendered 90 impervious to moisture.

4. A support for an insulator comprising a pin having a fibrous core and an outer electrolytically deposited metallic protective sheathing, whereby said core is rendered 95 impervious to moisture and fire resistant.

5. A support for an insulator comprising a pin having a fibrous core and an outer metallic protective sheathing covering the entire core.

6. A support for an insulator comprising a pin having a fibrous core and an outer metallic protective sheathing covering entirely 100 the exposed portions of the core.

7. A support for an insulator comprising a pin having a fibrous core and an outer electrolytically deposited metallic protective sheathing covering the entire core.
- 5 8. A support for an insulator comprising a pin having a fibrous core and an outer electrolytically deposited metallic protective

sheathing covering exposed portions of the core.

In testimony whereof, I have hereunto 10
subscribed my name this 30th day of Sept.
1918.

GEORGE IRVING GILCHREST.
